UNITED STATES PATENT OFFICE.

EDWARD A. HALBLEIB, OF ROCHESTER, NEW YORK, ASSIGNOR TO NORTHEAST ELECTRIC COMPANY, OF ROCHESTER, NEW YORK, A CORPORATION.

STARTING DEVICE FOR INTERNAL-COMBUSTION ENGINES.

1,024,447.

Specification of Letters Patent.

Patented Apr. 23, 1912.

Application filed September 6, 1910. Serial No. 530,785.

To all whom it may concern:

Be it known that I, EDWARD A. HALBLEIB, a citizen of the United States, and resident of Rochester, in the county of Monroe and State of New York, have invented certain new and useful Improvements in Starting Devices for Internal-Combustion Engines, of which the following is a specification.

This invention relates to starting devices for internal-combustion engines, of the type in which a source of compressed combustible mixture is connected with the cylinders of a multi-cylinder engine through an automatic distributor by which the mixture is directed to the proper cylinders.

The object of the invention is to produce a distributor for this purpose which shall be simple and compact in construction and reliable in operation, and in which the movement of the parts is reduced to a minimum.

To this end the invention consists in the mechanism hereinafter described, as it is defined in the succeeding claims.

25 The drawing represents a horizontal cross-section of an automatic distributing mechanism embodying the present invention, with an engine and a pump illustrated diagrammatically in connection therewith.

30 The device is represented as adapted for the control of a four-cylinder four-cycle motor in which the cylinders 1, 2, 3, and 4 fire successively in the order named.

35 The distributor of the illustrated device comprises a block 5 having an annular chamber 6 that is adapted to be supplied with explosive mixture. Any means for supplying such mixture under pressure may be used. In the drawing a hand pump 8 is 40 connected with the chamber 6 by a pipe 7, and with a mixer comprising an air-intake 9 combined with a needle-valve 10 that is supplied with liquid hydrocarbon through a pipe 11. A check-valve 12 is also shown 45 in the pipe 7 to prevent the mixture backing up into the pump.

The cylinders of the motor are, respectively, connected through pipes 13 with plugs 14 which are screwed into the block 5. 50 Within the central portion of the block 5, and in line with said plugs 14, are chambers 15 and 16, which contain slidable valves 17 and 18, respectively. The valves are beveled on their ends so as to seat tightly

against beveled seats at the ends of the 55 chambers. These valves automatically control the distribution of gas to the cylinders of the engines in a manner about to be described. Assume that the motor has come to rest with the pistons in the position 60 shown. In such case the piston of cylinder 1 would have passed compression and when stopped would be on the down-stroke; the piston of cylinder 2 would be under compression on the up-stroke and balanced 65 against the piston of cylinder 1; the piston of cylinder 3 would be at the beginning of the intake-stroke at the top of the cylinder, while the piston of cylinder 4 would be just beginning the exhaust-stroke. As the 70 piston of cylinder 1 moved upwardly and over the dead-center into the position shown, the air contained within the head of the cylinder was compressed and caused to flow through the pipe 13 and against the 75 valve 18, forcing the latter to move into the position shown in the drawing, and the compression in cylinder 2 had forced the valve 17 to move in the opposite direction into the position in which it is shown in the 80 drawing.

Ducts 19, 20, 21 and 22 connect, respectively, the chambers 15 and 16 with the annular chamber 6. These ducts are so placed that they are covered and uncovered by the movements of the valves 17 and 18, respectively. Accordingly it is obvious that when the engine stops in the position shown in the drawings, the valve 17 will have closed the duct 19, and the valve 18 will have closed the duct 22; leaving the ducts 20 and 21 open. If now the pump 8 is operated, the explosive mixture will be forced into the annular chamber 6, and thence through those passages that are open, viz: 90 the duct 20 which in connection with its pipe 13 leads to cylinder 2, and the duct 21 which in connection with its pipe 13 leads to cylinder 1. After those cylinders have been charged to a sufficient degree the ignition apparatus of the engine may be operated in any suitable manner to produce combustion in the cylinder whose piston has passed compression and is on the down stroke, as indicated in cylinder 1. The impulse so produced starts the movement of the engine and is shortly followed and reinforced by 95 an impulse in the cylinder 2. Thereafter

the engine operates in the usual manner, and the operation of the pump 8 is discontinued.

When the engine is running, each of the 5 valves 17 and 18 is moved in succession, first one way and then the other, in the chambers 15 and 16 by the pressure transmitted from the cylinders, so that in whatever position the engine may come to rest when 10 stopped the starting device is in position to charge those cylinders in which the pistons are on the compression stroke or the expansion stroke.

A piece of wire gauze 23 placed in each 15 of the pipes 13 prevents the fire in the cylinder from lighting the mixture back through said pipes.

I claim:

1. The combination with a plurality of 20 cylinders, of a distributor having a corresponding number of ducts communicating with said cylinders, respectively, and having also passages that afford communication between said ducts and extraneous means 25 adapted to charge them with an explosive mixture; valves in said passages, respectively, adapted to pass fluid under pressure only in the direction of said ducts; and valve means subjected to the fluid pressure 30 exerted by the compression strokes of the cylinders, and adapted to be operated thereby to open communication between the cylinders and passages leading to said source of explosive mixture, as and when the cylinders 35 are brought under compression, and at other times to close the communications between said passages and cylinders; substantially as shown and described.

2. The combination with a plurality of 40 cylinders, of a distributor having valve chambers with sliding valves therein, and having ducts in each valve-chamber each of which leads to a different cylinder, and having passages equal in number to the ducts 45 leading from each valve-chamber to a source of explosive mixture, the ducts and passages of each valve-chamber being so arranged with reference to each other that the valves are subjected to the fluid-pressure exerted 50 by the compression strokes of the cylinders and caused thereby to move to open com-

munication between the cylinder under compression and the source of fluid pressure, and at the same time to close the communications between such chamber and the other 55 cylinders; substantially as shown and described.

3. The combination with a plurality of cylinders, of a distributor having a chamber adapted to receive the explosive mixture 60 from a source of supply, valve chambers with sliding valves therein, each valve-chamber having ducts that lead in each case to a different chamber, and passages equal in number to the ducts leading from each 65 valve-chamber to the chamber for the explosive mixture, the ducts and passages of each valve-chamber being so arranged with reference to each other that the valves are subjected to the fluid pressure exerted by 70 the compression strokes of the cylinders and caused thereby to move to open communication between the cylinders under compression and the chamber for fluid mixture, and at the same time to close the communication 75 between such chamber and the other cylinders; substantially as shown and described.

4. In a starting device for internal-combustion engines a distributor comprising a 80 body having a straight valve-passage therethrough terminating in two outlet-openings adapted to be connected respectively with two cylinders of an engine, said body being provided with oppositely-disposed valve-seats adjacent the ends of said passage, and a valve-member movable in said passage and having its opposite extremities formed to engage and seat against said valve-seats alternatively to control the outlet-openings, the 85 body being provided further with an inlet-passage adapted to be connected with a source of combustible mixture, the inlet-passage opening transversely into said valve-passage and being controlled by a check-valve to prevent the return of combustible 90 mixture therethrough.

EDWARD A. HALBLEIB.
